DESIGN FOR A COMBINED SCARF AND EAR MUFFS

Elizabeth Estel, Theodore Boonshaft, and Edmond
Rovin, St. Louis, Mo.

Application May 24, 1939, Serial No. 85,186

Term of patent 3½ years

To all whom it may concern:

Be it known that we, Elizabeth Estel, Theodore Boonshaft, and Edmond Rovin, citizens of the United States, residing at St. Louis, in the State of Missouri, have invented a new, original, and ornamental Design for a Combined Scarf and Ear Muffs, of which the following is a specification, reference being had to the accompanying drawing, forming part thereof.

Figure 1 is a front perspective view showing a combined scarf and ear muffs showing our new design.

Figure 2 is an enlarged fragmentary front elevational view of the ear muff carrying portion.

Figure 3 is an elevational view of the opposite side of Figure 2.

We claim:

The ornamental design for a combined scarf and ear muffs, as shown.
